UNITED STATES PATENT OFFICE

126,122

DESIGN FOR A COMBINED LAMP BULB SOCKET AND SUPPORT THEREFOR

Paul Chilo, Chicago, Ill.

Application October 23, 1940, Serial No. 96,008

Term of patent 14 years

To all whom it may concern:

Be it known that I, Paul Chilo, a citizen of the United States, residing at Chicago, in the county of Cook and State of Illinois, have invented a new, original, and ornamental Design for a Combined Lamp Bulb Socket and Support Therefor, of which the following is a specification, reference being had to the accompanying drawing, forming part thereof.

In the drawing—

Fig. 1 is a front elevational view of a combined

lamp bulb socket and support therefor embodying my new design;

Fig. 2 is a side elevational view thereof; and

Fig. 3 is a top plan view thereof.

The dominant features of my design reside in the portions shown in full lines.

I claim:

The ornamental design for a combined lamp bulb socket and support therefor, substantially as shown and described.

PAUL CHILO.
